UNITED STATES PATENT OFFICE.

ALPHONSO T. PALMER, OF CHICAGO, ILLINOIS.

ANTICREEPER.

Application filed July 22, 1924. Serial No. 727,433.

To all whom it may concern:

Be it known that I, ALPHONSO THOMAS PALMER, a citizen of the United States, residing at Chicago, county of Cook, and State of Illinois, have invented a new and useful Improvement in Anticreepers, of which the following is a full, clear, and exact description.

The present invention relates broadly to means for preventing longitudinal creeping movement of rails, and more particularly to an anti-creeper effective intermediate adjacent ties, whereby said ties are effective through the tie plates carried thereby for resisting creeping of the rails.

At the present time it is customary to apply to a single panel of railway surface track a plurality of anti-creepers, the total number of anti-creepers so applied being determined mathematically by the maximum load to be resisted. As a matter of actual practice, however, it is practically impossible to apply a plurality of anti-creepers in such manner that all of the anti-creepers are uniformly and simultaneously effective. Even if they are so applied initially, the individual anti-creepers will not afford exactly the same amount of resistance to longitudinal movement, with the result that the rail will tend to move more relatively to some of the anti-creepers than to the others. This soon establishes a condition in which one or two anti-creepers in each panel are taking substantially the entire load at a given time. Under these conditions, the effective holding power of such anti-creepers is overcome and the rail moves successively relatively of the different anti-creepers as they come into operation.

It is one of the objects of the present invention to provide an anti-creeper capable of exerting a greater resistance to creeping movement of the rails, whereby the number of anti-creepers per panel of track may be materially reduced. In this manner, it is possible to initially apply a comparatively small number of anti-creepers in such manner that maximum effectiveness thereof is insured, and in such manner that throughout a given length of track substantially all of the anti-creepers will carry their full share of the load.

It is also common practice on a number of roads to so apply anti-creepers that a considerable area of contact is present between

the anti-creepers and the tie plates. I have found that such a condition is objectionable, as under the weaving action of the rails under the passing of loads thereover, the anti-creepers are worked loose from the rails, thereby destroying their usefulness. Also in a large number of the structures commonly used, there is contact between the steel anti-creeper and the wooden tie. Such a contact provides non-uniform conditions varying throughout the length of life of the anti-creeper, and becoming more and more objectionable as the tie wears.

The present invention has further for its object the provision of an anti-creeper in which not only is the area of contact of the anti-creeper with the tie plate reduced to a minimum, but also one in which the contact is continuously metal to metal.

In certain forms of anti-creepers, the construction is such that as long as the tendency of the rail to creep is in a given direction, the anti-creeper will grip the rail more and more tightly. Should the rail tend to creep in the opposite direction, however, such rail anchors are frequently loosened to an extent such that they thereafter exert no material holding action.

With certain forms of constructions now employed, portions of the anti-creepers are so designed that they will extend downwardly a sufficient extent to connect with the ballast. During the winter, the ballast frequently becomes frozen hard enough so that upon any tendency of the rail to back away, the anti-creeper is held by the ballast and is either broken or pulled loose from the rail.

The present invention has for other of its objects the provision of a construction such that the anti-creeper is equally effective against movement in either direction, and such that the ballast is never engaged to an extent sufficient to produce the objectionable operation referred to.

In the accompanying drawings there are shown, for purposes of illustration only, certain preferred embodiments of the present invention, it being understood that the drawings do not define the limits of my invention, as changes in the construction and operation disclosed therein may be made without departing either from the spirit of my invention or the scope of my broader claims.

In the drawings:—

Figure 1 is a top plan view of a portion of track illustrating one form of anti-creeper in operative position between adjacent ties;

Figure 2 is a transverse sectional view, on an enlarged scale, on the line II—II of Figure 1;

Figure 3 is a longitudinal sectional view, on an enlarged scale, on the line III—III of Figure 1;

Figure 4 is a view similar to Figure 1, illustrating a slightly modified embodiment of the invention;

Figure 5 is a transverse sectional view through a rail and an applied anti-creeper illustrating still another embodiment of the present invention;

Figure 6 is a view similar to Figure 5 illustrating a further modification;

Figure 7 is a perspective view of the gripping element shown in section in Figure 6, and

Figure 8 is an exploded view of certain portions of the anti-creeper shown in Figure 6.

In carrying out the present invention, there is formed a gripping element 2 of suitable steel, preferably by rolling, to provide therein a groove 3 adapted to be driven on to one edge of a rail base so as to effectively grip the same. At some suitable point within the gripping element, and preferably in the under lip 4 thereof, are formed coaxial threaded openings 5 having a wall 6 of solid metal therebetween. Threaded into the openings 5 are thrust rods 7 having a combined length which is determined by the average distance between tie plates 8 on adjacent ties 9. It will be understood that by reason of the threaded engagement of the rods 7 with the gripping element, it is possible to vary the overall length of the anti-creeper in such manner that it will effectively and tightly engage the edges of the tie plates 8 on adjacent ties.

While the openings 5 may be located at any desired point in the gripping element, they are preferably formed therein in such manner that the rods 7 will engage the edges of the tie plates intermediate the spikes 10 on opposite sides of the rail. In this manner, any load transmitted from the anti-creeper to the tie plates through the thrust rods is taken up by all of the fastening means of the tie plate to which the load is transmitted. Due to the fact that the point of engagement between the thrust rods and the tie plates is intermediate the spikes on opposite sides of the rail, there is no tendency of the tie plates to be thrown out of their normal positions. This insures a straight thrust on the gripping element 2 without any tendency to twist the same from gripping engagement with the edge of the rail base.

In Figure 4 of the drawings there is illus-

trated a slightly different form of the invention, in which a plurality of gripping elements 2' is utilized in place of the single gripping element before described. In this construction, each of the gripping elements may be provided with a single threaded opening, these openings preferably being right and left handed to receive the threaded ends of the single thrust rod 7'. While with this form of my invention, it is possible to utilize a plurality of gripping elements, I have found that on account of the increased area of contact between these elements 2' and the tie plates 8', the structure is not as satisfactory for all purposes as the structure just described.

With both of the forms of the invention heretofore referred to, it will be understood that only one of the openings in the gripping element 2 or the opening in only one of the gripping elements 2' need be threaded, as the adjustment may be obtained by a single threaded engagement. Preferably, however, all of the openings are threaded, as in this manner a correspondingly greater or less overall length can be obtained, thereby adapting the rail anchor for use even with ties spaced irregularly. On the other hand, where it is desired to operate under fixed conditions with respect to the spotting of the tie plates, the thrust rods may be rigidly secured in position within the gripping element or elements without any necessity for a threaded engagement.

In some cases it may be desirable to provide some supplemental means cooperating with the gripping element for positively insuring accurate positioning thereof and for preventing any tendency of the same to work off the rail base. In Figure 5 there is illustrated one construction admirably suited for this purpose. In accordance with this embodiment of my invention, the under lip 4' of the gripping element is provided with a hook shaped lug 11 extending lengthwise of the gripping element adjacent the inner edge thereof. This lug is adapted to cooperate with one end of a clip 12, the opposite end of which is shaped to engage the edge of the rail base opposite the gripping element. Due to the distance between ties, the clip 12 may conveniently be formed of spring steel, and may be driven lengthwise of the rail over the lug 11 and into the position illustrated in Figure 5.

In Figures 6, 7 and 8 there is illustrated a modification of the invention embodying features similar to those illustrated in Figure 5. In this form, however, the lug 11 is omitted entirely, and the gripping element is formed with a longitudinally extending slot 14 intersecting the opening or openings 15 in the lower lip of the gripping element. With this construction, the thrust rod or rods 16 are formed with a longi-

tudinally extending recess 17 adapted to receive the correspondingly shaped head 18 of a fastening clip 19. With this construction, the anti-creepers may be driven 5 into position on a rail, and the fastening clip then driven into position, or the fastening clip may be placed in position prior to driving the gripping element on to the rail. In either case, the outer end 20 of the fastening clip will be bent upwardly around the edge of the rail base opposite the gripping element. To permit this bending operation, it will be understood that the main body of the fastening clip may be formed of spring 15 steel with an untempered outer end, or the entire body of the clip may be of such characteristics that bending at any point may take place.

It will be apparent that in the form of my invention illustrated more particularly in Figure 1 of the drawings, the diameter of the thrust rods 7 is not limited to the thickness of the tie plates at the portions thereof beneath the rails. This is true for the reason that the ends of the thrust rods will readily embed themselves in the upper surface of the tie, either under the action of the spikes 10 when they are driven into place, or by reason of the passage of a train 25 over the track. In either case, the depressions so formed in the ties will cooperate with the thrust rods to some extent to counteract any tendency of the anti-creepers to move laterally from the rail. This enables 30 the parts of the anti-creepers to be dimensioned with respect to the load to be carried thereby, without regard to limitation by reason of dimensions of standard rail-way appliances.

With all of the forms of my invention, the length of the gripping elements may be such as to give the desired area of contact between the same and the rail base, thereby overcoming the limitations imposed in structures 45 in which the gripping element is mounted within a suitable opening or recess within the tie plate. This enables me to provide an anti-creepers having a materially greater holding power than anti-creepers of the character referred to, whereby it is possible for me to reduce the number of anti-creepers per unit of track section as hereinbefore pointed out.

Further advantages of the present invention 55 arise from the provision of an anti-creepers which is equally effective in resisting any tendency of the rail to move longitudinally in either direction, and which is maintained out of such engagement with the ballast as will prevent operation as desired.

I claim:

1. A rail anti-creepers, comprising a rail gripping element adapted to grip one edge only of a rail base intermediate adjacent ties, and means cooperating with said ele-

ment to transmit loads therefrom to the tie plates on said ties to prevent creeping in either direction.

2. A rail anti-creepers, comprising a rail gripping element adapted to engage one edge of a rail base intermediate adjacent ties, and means adjustably cooperating with said element to vary the overall length of the element and means to transmit loads therefrom to the tie plates on said ties to prevent creeping in either direction.

3. A rail anti-creepers, comprising a rail gripping element adapted to engage one edge of a rail base intermediate adjacent ties, and thrust rods projecting from opposite ends of said gripping element, at least one of said thrust rods having a threaded engagement with the gripping element.

4. A rail anti-creepers, comprising a rail gripping element having an opening therein of a shape determined by the corresponding section of the rail base to be engaged thereby, said gripping element being adapted to be driven laterally on to the rail base intermediate adjacent ties, and means preventing relative longitudinal movement between said gripping element and the tie plates on said ties to prevent creeping in either direction.

5. A rail anti-creepers, comprising a rail gripping element adapted to be driven on to one edge of a rail base intermediate adjacent ties, means cooperating therewith to transmit loads therefrom to the tie plates on said ties to prevent creeping in either direction, and means engaging said element and the edge of the rail base opposite the gripping element.

6. A rail anti-creepers, comprising a rail gripping element adapted to be driven on to one edge of a rail base intermediate adjacent ties, means cooperating therewith to transmit loads therefrom to the tie plates on said ties to prevent creeping in either direction, and movable means engaging said element and the edge of the rail base opposite the gripping element.

7. A rail anti-creepers, comprising a rail gripping element adapted to be driven on to one edge of a rail base intermediate adjacent ties, means cooperating therewith to transmit loads therefrom to the tie plates on said ties to prevent creeping in either direction, and means movable longitudinally of the rail adapted to engage said gripping element and a portion of the rail base opposite the same.

8. As an article of manufacture, a rail anti-creepers comprising a rail gripping element adapted to be driven on to one edge of a rail base, and a thrust rod adjustably mounted therein.

9. As an article of manufacture, a rail anti-creepers comprising a rail gripping element adapted to be driven on to one edge

of a rail base, and a plurality of thrust rods adjustably mounted therein.

10. As an article of manufacture, a rail anti-creeper comprising a rail gripping element adapted to be driven on to one edge of a rail base, and a plurality of thrust rods adjustably mounted therein in coaxial alignment.

11. As an article of manufacture, a rail anti-creeper comprising a rail gripping element adapted to be driven on to one edge of a rail base, and a thrust rod adjustably mounted therein, said thrust rod being adapted to extend below the rail base and between the edges thereof.

12. As an article of manufacture, a rail anti-creeper comprising a rail gripping element adapted to be driven on to one edge of a rail base, and a plurality of thrust rods adjustably mounted therein, said thrust rods being adapted to extend below the rail base and between the edges thereof.

13. A rail anti-creeper, comprising means adapted to engage a portion of the rail base intermediate adjacent ties, and thrust means projecting therefrom for engaging the tie

plates on adjacent ties at a point within the limits of the spike openings therein.

14. A rail anti-creeper, comprising a rail gripping element adapted to engage a rail base intermediate adjacent ties, and means cooperating with said element below the rail base and intermediate the edges thereof to transmit loads therefrom to the tie plates on both of said ties to prevent creeping in either direction, said means being adjustably connected to said element whereby the overall length of the element and means may be varied.

15. A rail anti-creeper, comprising a rail gripping element adapted to engage a rail base intermediate adjacent ties, and means cooperating with said element below the rail base to transmit loads therefrom to the tie plates on both of said ties to prevent creeping in either direction, said means being adjustably connected to said element whereby the overall length of the element and means may be varied.

In testimony whereof I have hereunto set my hand.

ALPHONSO T. PALMER.
